UNITED STATES PATENT OFFICE.

LEON W. PARSONS, OF CAMBRIDGE, MASSACHUSETTS, AND STEWART P. COLEMAN, OF CORPUS CHRISTI, TEXAS, ASSIGNEES TO STANDARD DEVELOPMENT COMPANY, OF NEW YORK, N. Y., A CORPORATION OF DELAWARE.

PROCESS OF PURIFYING HYDROCARBONS.

No Drawing.

Application filed November 10, 1922. Serial No. 599,966.

The present invention relates to the art of purifying hydrocarbons and will be fully understood from the following description.

In proceeding according to the present invention various stocks as desired may be treated, whether crudes, as may be advantageous in some circumstances, or fractions thereof. To the oil to be treated, there is added an oxidizing agent, copper oxid, CuO, for example, being especially advantageous, although with some oils lead oxid may be used. The precise amount of oxid will vary with the particular stock treated and the product in view, running in general from 1 to 15% by weight. With copper oxid when working with lubricating stocks from coastal crudes we have found up to 10% advantageous, 2 to 6% giving the best results. The oil is warmed, the temperature depending upon the particular stock being treated; light stocks will of course not be warmed to a temperature of vaporizing loss, but with heavy stocks temperatures above 120° F. and up to 350° F. are especially advantageous. Different and higher temperatures can be used depending on the nature of the stock.

After subjecting the oil to this treatment for from 15 to 60 minutes, varying with the stock, the strength of the oxidizing agent and the amount of treatment desired, sufficient agitation being employed to insure adequate diffusion and contact of the treating agent, the oil is drawn off from the sludge and metallic copper residue and is treated with an alkali. This may be done in any convenient container, but desirably is combined with a final distillation and in such case most advantageously the alkali may be provided by a charge of caustic soda previously placed in the still and heated sufficiently to drive off water. In general the amount of caustic soda required will run between about 2 to 8 or 10 per cent. An excess of alkali does no serious damage, but is wasteful and increases gumming in the still. Other alkalies can be used, though less desirably, for instance, caustic potash, and soda-lime mixture, or caustic soda and carbonate mixture. The oil is now distilled off as desired. With heavy stocks it is advantageous to use vacuum distillation.

If desired the cupric oxid or other oxidiz-

ing agent and the alkali can be used simultaneously in treating the oil. A final distillation is advantageous and with heavy stocks vacuum distillation may be employed if desired. Where preferred the entire treatment may be carried out in a still and the oil may then be distilled off. In some cases, as when asphalt or tarry suspension is present, the hydrocarbon stock may preliminarily be given a light or purifying treatment with sulfuric acid, neutralizing and washing as usual, and then be treated with copper oxide or the like and with the alkali successively or simultaneously.

While in describing our invention we have referred to certain specific details it will be understood that this is by way of illustration and explanation, and is not limitative. Nor is the invention to be regarded as dependent upon the accuracy of any theories mentioned in connection with explanation of the advantageous results attained, but on the other hand the invention is to be regarded as limited only as defined in the following claims, in which it is our intention to claim all inherent novelty as broadly as the prior art permits.

What we claim is:

1. The improvement in the art of purifying heavy hydrocarbons, which comprises adding 1-10% of cupric oxid to the hydrocarbon stock and heating to 120° F. to 350° F. for 15 to 30 minutes while agitating, then introducing the hydrocarbons into a still containing a charge of caustic soda amounting to 2-8%, and distilling the hydrocarbons under a vacuum.

2. The improvement in the art of purifying hydrocarbons, which comprises adding 1-10% of copper oxid to the hydrocarbon stock and heating to a temperature short of vaporization for 15 to 30 minutes while agitating, then introducing the hydrocarbons into a still containing a charge of caustic soda amounting to 2-8% and distilling the hydrocarbons.

3. The improvement in the art of purifying hydrocarbons, which comprises adding 1-10% of copper oxid to the hydrocarbon stock and heating to a temperature at all times short of vaporization, while agitating, then introducing the hydrocarbons into a

still containing a charge of caustic soda amounting to 2-8% and distilling the hydrocarbons.

4. The improvement in the art of purifying hydrocarbons, which comprises subjecting the hydrocarbon stock to a purifying treatment with sulfuric acid, settling and separating the sludge and residual acid from the hydrocarbon stock and subsequently 5 treating the acid treated oil with copper oxide while heating to a temperature at all times short of vaporization, then introducing into a still containing a charge of caustic soda, and distilling the hydrocarbons until 10 a vacuum.

5. The improvement in the art of purifying hydrocarbons, which comprises adding a mineral oxide having oxidizing properties to the hydrocarbon stock and heating to 20 a temperature at all times short of vaporization while agitating, then introducing the

hydrocarbon stock into a still containing a charge of caustic soda and distilling the hydrocarbons under a vacuum.

6. The improvement in the art of purifying hydrocarbons, which comprises adding a mineral oxid having oxidizing properties to the hydrocarbon stock and heating to a temperature at all times short of vaporization, then introducing the hydrocarbon stock into 25 a still containing a charge of caustic soda, and distilling the hydrocarbons. 30

7. The improvement in the art of purifying hydrocarbons, which includes the steps of adding 2 to 10% of copper oxid and heating to a temperature at all times short of vaporization while agitating, then subjecting the hydrocarbons to the action of caustic 35 soda.

LEON W. PARSONS.
